UNITED STATES PATENT OFFICE.

WALTER P. MURPHY, OF CHICAGO, ILLINOIS.

COMBINED UNCOUPLING-LEVER AND COUPLING-POSITIONING DEVICE.

1,314,283.

Specification of Letters Patent. Patented Aug. 26, 1919.

Original application filed December 7, 1916, Serial No. 135,626. Divided and this application filed June 18, 1917. Serial No. 175,414.

To all whom it may concern:

Be it known that I, WALTER P. MURPHY, a citizen of the United States, residing at Chicago, in the county of Cook and State 5 of Illinois, have invented certain new and useful Improvements in Combined Uncoupling-Levers and Coupling-Positioning Devices, of which the following is a specification.

10 Couplers have from 3 to 3.5 inches lateral motion on carrier irons, normally, but when the draft sills are damaged it is possible for the coupler to have a greater lateral movement.

15 When cars are left standing in railway yards, and about industrial plants, in which the outside rail or curves is considerably higher than the inside rail, the coupler is thrown, swings, or slides over toward the 20 inside rail. It is also frequently necessary to couple cars on a sharp curve, in which event it is necessary to push both couplers as far as possible to the inside of the curve, so that the couplers will engage each other.

25 In this connection the Interstate Commerce Commission have reported that many accidents have been caused by the trainmen attempting to position the couplers on the carrier iron to suit requirements, so that it 30 would meet the opposing coupler, this operation making it necessary for a man to place some portion of his body, usually his foot or arm between the cars, generally while they are in motion. A great many 35 employees have had feet or hands crushed in this way. The annual reports show that over 10% of coupler accidents are due to adjusting the couplers.

The primary object of my invention is to 40 provide means whereby the coupler may be positioned without the operator placing any portion of his body between the cars, and to hold it there while the cars are being coupled.

A further object of my invention is to 45 provide a positioning device which will not, in its installation, interfere with the air brake or signal couplings, or lock pins, and which requires no alteration of any part of a car or locomotive.

50 A further object of my invention is to provide a combined uncoupling lever and positioning device, whereby no additional bolts and brackets are necessary; and with these and other objects in view my invention con-

sists of the parts and combination of parts 55 as will be hereinafter pointed out.

In the drawings:—

Figure 1 is an end elevation of a part of a car to which my invention is attached.

Fig. 2 is a top plan view of the same, the 60 end sill being in section.

Fig. 3 is a detail perspective view of the outside bracket.

Figs. 4, 5, 6, 7, and 8 are detail views of the outer end of the hand operated lever 65 and its bracket showing the different positions assumed by the lever and its handle in operation.

This application is a division of my application filed December 7, 1916, Serial No. 70 135,626.

The reference numeral 1 designates a car to which the end sill 2 is secured. The coupler 3 is of standard construction and is provided with a lock pin 4.

75 Many cars are equipped with the swing carry iron shown in the drawing. The carrier 5 being pivotally mounted on the swingingly mounted arms 6, the trunnions 7 of which bear on the block 8. The object 80 of a swinging carry iron is to permit it to swing with the coupler under service conditions thereby eliminating relative lateral movement between the coupler and carry iron. Any preferred type of swinging 85 carry iron may be used with my invention. In fact the carry iron need not be a swinging one as far as my invention is concerned as it is one of the purposes of my invention to center a coupler irrespective of any particular type of carry iron.

The inner end of the operating rod 11 is preferably revolvably mounted in a bracket 10 suitably secured to a car, positioned to permit of the successful operation of the parts. 95 Any preferred type of bracket may be used.

The inner end of the operating rod or lever 11 is bent downward and outward as at 12 and thence forward as at 13 parallel with the main body of the rod; the end portion being reduced in diameter as at 14 and provided with suitable screw threads; the reduced portion 14 being adapted to pass through the eye of the lock pin 4, of the coupler, to which pin it is secured by means 100 of nuts 15 or other suitable devices.

The outer end of the rod 11 is provided with a depending handle 16 with which it

has a pivotal connection as clearly shown, the end of the rod being reduced as at 17 while the upper end of the handle is forked to receive the reduced portion 17 and is secured thereto by means of the pin 18.

The upper end of the handle 16 is enlarged to form a head 19 whereby shoulders 20, 21, are formed at the juncture of the head and handle, to be hereinafter referred to.

The bracket for the outer end of the rod 11 comprises a base plate 22 having suitable openings 23 through which bolts, rivets, and the like may pass, whereby the bracket may be secured to the end of the car. A loop is secured to the base plate 22 each side arm of which is bent at substantially right angles thereby constituting bottom arms 24, 25, and front arms 26, 27, the outer end of the arms 26, 27 being connected by a cross piece 28 which constitutes a stop to limit the upward movement of the handle 16; the arms 24, 25, 26, 27, being curved at their juncture as clearly shown in Figs. 3, 7, 8.

Normally the handle 16 is in the position shown in Fig. 4. In the event that the coupler has moved over toward the right, under the conditions hereinbefore mentioned, and it is desired or necessary to center it, the handle 16 is moved inward to the position shown in Fig. 5, the shoulder 21, bearing on the arm 24 of the loop, the arm 24 functioning as a fulcrum whereby the coupler, through the rod is pulled toward the left and centered. In the event that it is desired or necessary to move the coupler toward the left, the handle 16 is moved to the position shown in Fig. 6 in which case the shoulder bears on the arm 25, of the loop, said arm functioning as a fulcrum.

To operate the lock pin 4, the handle 16 is pulled upward as shown in Fig. 8, whereupon by reason of the crank formation of the inner end of the rod 11 the lock pin is pulled upward to release the knuckle of the coupler, the shoulders 20, 21, of the handle sliding on the top rounded face of the arms 24, 25, 26, 27, of the loop of the outside bracket.

Many changes may be made in the details of construction which I have employed for the purposes of illustrating my invention without departing from the spirit of my invention, the basic principle of which is a coupler pin operating rod or lever which is attached to the coupler in such manner that it can be used to operate the lock pin, throw the knuckle, or lock set the coupler or position the coupler laterally as desired.

What I claim is:—

1. In a device of the character described, the combination with a car coupler, laterally movable at its outer end with respect to the car, of a rod revolvably mounted on the car and operatively connected at its

inner end to said coupler, a common bearing and fulcrum in which the outer end of the rod is operatively mounted, and an operating handle at the outer end of said rod, whereby said rod may be revolved in and the handle fulcrumed on said bearing and fulcrum to operate the coupler and to position the coupler in alinement with a coupler on an adjacent car.

2. In a device of the character described, the combination with a car coupler laterally movable at its outer end with respect to the car, of a rod revolvably mounted on the car and operatively connected at its inner end to said coupler, a common bearing and fulcrum in which the outer end of said rod is operatively mounted, and an operating handle pivotally mounted on the outer end of said rod, whereby said rod may be revolved in and fulcrumed on said outer bracket to operate the coupler and to position the coupler in alinement with the coupler on an adjacent car.

3. In a device of the character described, the combination with a car coupler laterally movable at its outer end with respect to the car, of a rod revolvably mounted on the car and operatively connected at its inner end to said coupler, a bracket having a common bearing and fulcrum in which the outer end of the rod is pivotally mounted, and an operating handle pivotally mounted on the outer end of said rod and depending through the bracket, whereby said rod may be revolved in and the handle fulcrumed on said outer bracket to operate the coupler and to position the coupler in alinement with the coupler on an adjacent car.

4. In a device of the character described, the combination with a coupler operating rod revolvably mounted in brackets on a car; one of said brackets comprising a base and an angular loop extending forwardly from said base.

5. In a device of the character described, the combination with a coupler and its lock and means for moving said lock to unlocked position, said means including a lever rotatably mounted and operatively connected with said lock, and a bracket for the outer end of said lever, said bracket being substantially U shaped and means to limit the revolution of said lever.

6. In a device of the character described, the combination with a laterally movable coupler, of means for shifting said coupler, said means including a bodily shiftable rod operatively connected at its inner end to said coupler, a bracket having a common bearing and fulcrum in which the outer end of the rod is mounted, and a handle pivotally connected to the outer end of the rod and depending through said bracket and between the fulcrum.

7. In a device of the character described,

- a bracket having a common bearing and fulcrum.
8. In a device of the character described, a bracket comprising a base, spaced parallel arms extending forwardly from said base and connected at their outer ends, said arms being bent upwardly at substantially right angles.
9. In a device of the character described, 10 the combination with a lever, and a handle pivotally mounted on the outer end of said lever, of a bracket in which the outer end of the lever is revolutely mounted, said bracket comprising a base, parallel and angularly 15 upwardly deflected arms extending from said base, a stop connecting the outer ends of said arms, whereby said arms constitute a bearing on which the lever may be revolved and fulcrumed for said handle whereby 20 the lever may be shifted bodily.
10. In a device of the character described, the combination with a lever, and a handle pivotally mounted on the outer end of said lever, rounded bearings on said lever near 25 the upper end thereof, of a bracket in which the outer end of the lever is revolutely mounted, said bracket comprising a base, parallel angularly upwardly deflected arms extending from said base, a stop connecting 30 the outer ends of said arms, whereby said arms constitute a bearing on which the lever may be revolved and fulcrums for said handle, engaged by the bearings on the handle whereby said lever may be shifted bodily.
- 35 11. In a device of the character described, the combination with a coupler, the outer end of which is movable relatively to a car, of means for shifting said coupler laterally, said means including a lever and a substantially 40 **U**-shaped member secured to a car to form a closed loop, the legs of the loop forming fulcrums for said lever either of which is adapted to be engaged selectively by said lever for shifting said coupler laterally.
12. In a device of the character described, the combination with a laterally movable coupler, of means for shifting said coupler laterally, said means involving a lever and 50 a closed loop secured to a car, the legs of said loop forming fulcrums for said lever either of which is adapted to be engaged selectively by said lever, for shifting said coupler laterally.
- 55 13. In a device of the character described, the combination with a laterally movable coupler, of means for shifting said coupler laterally, said means involving a lever, and a closed loop secured to a car, said loop being 60 disposed in a substantially horizontal plane, the legs of said loop forming fulcrums for said lever either of which is adapted to be engaged selectively by said lever for shifting said coupler laterally.
14. In a device of the character described, 65 the combination with a coupler, the outer end of which is movable laterally relatively to a car, of means for shifting said coupler laterally, said means including a lever and two fulcrum members secured to the car, 70 the outer ends of said fulcrum members being connected, said fulcrum members forming fulcrums for said lever, either of which is adapted to be engaged selectively by said lever for shifting said coupler laterally. 75
15. In a device of the character described, the combination with a laterally movable coupler, of means for shifting said coupler laterally, said means including a lever, and a closed loop secured to a car, the sides of 80 said loop forming fulcrums for said lever, either of which is adapted to be engaged selectively by said lever for shifting said coupler laterally.
16. In mechanism of the character indicated, the combination with a laterally movable coupler, of means for shifting said coupler laterally, said means involving a lever and a **U**-shaped member secured 85 through its legs to the car, the legs of said **U**-shaped member forming fulcrums for said lever either of which is adapted to be engaged selectively by said lever for shifting said coupler laterally. 90
17. In a device of the character described, 95 a bracket provided with a portion constituting both a bearing and a fulcrum.
18. In a device of the character described, the combination with a car coupler, laterally movable at its outer end with respect 100 to the car, of a rod revolutely mounted on the car and connected at its inner end to the said coupler, a bracket provided with a portion constituting both a bearing and a fulcrum in which the outer end of the rod is 105 mounted, and an operating handle at the outer end of said rod, whereby the rod may be revolved in and the handle fulcrumed on said bearing and fulcrum to operate the coupler and to position the coupler in alinement 110 with a coupler on an adjacent car.
19. In a device of the character described, a bracket having a portion constituting a bearing and a fulcrum, and an operating handle mounted on said bearing and fulcrum, and a rod connecting said handle and the coupler. 115

WALTER P. MURPHY.
